SUBSCRIBER'S STATION FOR TELEPHONE SYSTEMS

Clement M. Theillaumas, Lyon, France, assignor to International Standard Electric Corporation, New York, N. Y., a corporation of Delaware

Application March 24, 1943, Serial No. 480,415
In France October 15, 1941

10 Claims. (Cl. 179—81)

1
The present invention relates to telephone system and more particularly to the circuits for a subscriber's telephone station in rural or other telephone systems with manual or semi-automatic service.

One object of the invention is to provide a manually operated or semi-automatic system including a subscriber's telephone station which contains neither a calling magneto nor a local supply battery for the transmitter microphone.

Another object of the invention is to provide telephone systems of the type described including subscriber's station circuits insuring proper operation of these stations with current supplied from an exchange.

A still further object of the invention is to provide in a telephone system including a subscriber's station without magneto or battery, effective means for calling an exchange or another subscriber.

Still a further object of the invention is to provide means whereby the mechanism at a subscriber's station for calling an exchange or another subscriber without magneto or battery is prevented from interfering with the proper operation of the ringer at the subscriber's station upon reception of an incoming call.

Still another object of the invention is to provide a subscriber's station for manual or semi-automatic service which, with regard to a considerable part of its structure, is similar to and even interchangeable with a subscriber's station for full-automatic service.

These and other objects are accomplished, according to the present invention, by the arrangement and combination of circuits and circuit elements set forth in the following description, defined in the appended claims and illustratively exemplified in the accompanying drawing, the single figure of which is a wiring diagram of a subscriber's telephone station according to the invention and of some of the elements at the exchange to which the subscriber's station is connected.

Generally, in the drawing illustrative of this invention, all contacts are shown in their rest positions.

The feed battery 1 of the exchange B is permanently connected to the wires *a* and *b* of the line L over two resistances of suitable value, such as, for instance, of 5000 ohms each. The line relay 4 is connected across the line wires *a* and *b* in series with *a*, for instance electrolytic, condenser 5 which serves to isolate the relay 4 from the battery 1. The condenser 4 is, thus, kept

charged as long as the junction between the exchange B and the subscriber's station A remains inactive.

The subscriber's station A contains the receiver 6 and the transmitter microphone 7 inductively connected in the usual manner by means of the transformer 8. The ringer 9 is inserted in a circuit loop which is closed by the lower one of the contacts 10 of the cradle switch when the receiver 6 rests on the cradle. This loop is inserted between the wires *a* and *b* through a rest contact of a calling switch 11 and it contains the usual condenser 12 to protect the ringer 9 against direct current. During a conversation, the receiver 6 and the transmitter microphone 7 are both connected to this same rest contact of the switch 11 because of the closing of the contacts 13 of the cradle switch which are kept open as long as the receiver rests on its cradle or support.

20 The calling device comprises a series of condensers 14 to 16 associated, respectively, with pairs of double contact switches 17—18, 19—20, 21—22, which, in their rest positions shown, connect the condensers 14, 15 and 16 in parallel to the battery 1 through a suitable resistance 23, thus keeping said condensers charged.

The initiation of a call by the subscriber necessitates excitation of the line relay 4 at the exchange B. This result is accomplished by the 30 discharge in series of the condensers 14, 15 and 16 which is caused by a simultaneous switching over of all the double contact switches 17—22 upon their (right hand) working contacts. This operation may be effected by the subscriber through the operation of a special calling switch control mechanism, such as the depression of a single control button for all said switches or the manipulation of a dial having a single finger hole. The switch 11 is mechanically connected with 40 the switches 17 to 21, so as to eliminate during the discharge of the condensers 14—16 into the line L the resistance 23 which would render the discharge current too feeble.

The calling switch control mechanism may be 45 constructed in any desired simple manner. Since it does not form a part of the present invention, it is not shown nor described in detail.

The reception of incoming calls at the subscriber's station, presupposes the transmission 50 from the exchange over the wires of the line L of an alternating current of low frequency (such as 16, 25 or 50 P. P. S.) with a potential difference which may exceed 100 volts. The ringer 9 is then actuated. This alternating current would be apt 55 to cause a deterioration of the electrolytic con-

densers 14-16 formed under a much lower tension of about 30 volts, if it were not for the resistance 23. Moreover, this resistance 23 gives to the leakage circuit formed by said condensers a sufficiently strong impedance to prevent any interference with the normal operation of the ringer 9.

When the subscriber takes off the receiver, either after emission or upon reception of a call signal, the contact 13 of the cradle switch is closed, so that the transmitter microphone 7 is inserted into the supervisory loop of the operator at the exchange B, and the microphone 7 is, in this manner, supplied with current over the line L from the exchange battery 1. Simultaneously, the contacts 10 are opened, thus disconnecting the leakage circuit through the condensers 14-16 and the alarm circuit and preventing any weakening of the talking currents.

The line relay 1 may be protected, instead of by means of a condenser 5, by means of a unidirectional rectifier connected in such a manner that it passes the discharge current of the condensers 14 to 16 while blocking the condenser charging current.

Owing to the omission at the substation of the feed battery for the transmitter microphone and of the calling magneto, it is further possible, according to the invention, to construct a subscriber's station which can be adapted to telephone systems with full automatic service as well as to systems with manual or semi-automatic service. The receiver, the transmitter microphone, the induction coil and the ringer can be identical in both cases. Only the electrolytic condensers and the spring contact combinations necessitate a different wiring. Thus, the subscriber's stations according to the invention, provide for a more complete standardization of the material and equipment and, moreover, each station in a full-automatic system can be easily converted into one of a manual or semi-automatic system according to the invention, or vice versa.

The line condensers 5 or the rectifiers to be substituted therefor, may be provided in the detachable line relay block of a standardized semi-automatic exchange installation. For this purpose, the condensers or rectifiers are inserted into a flat casing mounted on the collapsible rear wall of the relay support. This requires only a small modification in the wiring on the inside and no change at all in the outside wiring.

It should be noted that the introduction of a subscriber's station of the type set forth above into a telephone network with manual or semi-automatic service makes it necessary to hold the wire lines permanently under a current supplied by the exchange battery. However, this permanent application of current has no detrimental effect upon the insulation of the line, because the potential difference of the supply battery 1 does not exceed 30 volts at the end of the charge, whereas, if a call signal is generated by the usual magneto the peak tensions may exceed 200 volts. On the other hand, a high resistance 2, 3 is provided, in the present arrangement, between each terminal of the battery 1 and the corresponding line wire. Thus, even in the case of a short circuit of the line directly outside of the exchange, the permanent maximum load is less than 3 milliamperes, which is practically negligible. Finally, since the supervision is usually effected by means of a loop at the subscriber's station, no danger is involved in introducing into said loop the

transmitter microphone 7 to replace a dead resistance.

It will be understood that the invention is not limited to the embodiment shown and described but may be modified or varied in numerous ways within the scope of the following claims.

I claim:

1. A telephone system comprising an exchange, a subscriber's station, line wires connecting the exchange with the subscriber's station, a supply battery connected across the line wires at the exchange, circuits at the subscriber's station including an operator's supervision loop, and a transmitter microphone inserted in said supervision loop, so as to be supplied with current from said supply battery when said supervision loop is closed.

2. A telephone system, as claimed in claim 1, including two high resistances inserted between the terminals of said battery and the corresponding line wires respectively.

3. A telephone system comprising an exchange, a subscriber's station, line wires connecting the exchange with the subscriber's station, a supply battery connected across the line wires at the exchange, a line relay to control outgoing call signals connected across the line wires at the exchange, a blocking device connected across said line wires in series with said relay to prevent the latter from being excited by the battery current, and an energy storage circuit connected across said line wires at the subscriber's station when the latter is not busy, said storage circuit containing at least one condenser, and subscriber controlled means to reverse the connection of said condenser in said storage circuit when a call signal is to be transmitted from said subscriber's station, said blocking means being adapted to pass current impulses emitted from said condenser upon reversal of its connection in said storage circuit to permit excitation of said relay.

4. A telephone system, as claimed in claim 3, in which said storage circuit contains a plurality of condensers normally connected in parallel with one another, and means to connect said condensers in series upon reversal of their connection in said storage circuit.

5. A telephone system, as claimed in claim 3, in which said condenser is an electrolytic condenser.

6. A telephone system, as claimed in claim 3, in which said subscriber's station includes a ringing circuit connected across said line wires in parallel with said storage circuit when subscriber's station is not busy, said ringing circuit containing a condenser and said storage circuit having a resistance greater than that of said ringing circuit.

7. A telephone system, as claimed in claim 3, in which said storage circuit contains a resistance and means to short-circuit said resistance upon reversal of the connection of said condenser in said circuit.

8. A telephone system, as claimed in claim 3, in which said subscriber's station includes a cradle switch capable of assuming a non-busy and a busy position, said cradle switch including a contact connecting said storage circuit to said line wires when said switch is in its non-busy position and breaking said storage circuit when said cradle switch is in its busy position.

9. A telephone system comprising an exchange, a subscriber's station, a line circuit connecting said exchange with said subscriber's station, a supply battery connected across the line circuit at the exchange, a line relay to control outgoing call signals connected across the line circuit at

the exchange, a blocking device connected across the line circuit in series with said relay to prevent the latter from being excited by the battery current, said subscriber's station containing an operator's supervision loop including a transmitter microphone, a receiver circuit, a ringing circuit including a condenser, and a storage circuit containing at least one condenser and a resistance, subscriber controlled means at said subscriber's station to reverse the connection of said condenser in said circuit and to short circuit said resistance when a call signal is to be transmitted from said subscriber's station, said blocking means being adapted to pass current impulses emitted from said condenser upon reversal of its connection in said storage circuit to permit excitation of said relay, and a cradle switch at said subscriber's station capable of assuming a non-busy and a busy position, said cradle switch in-

cluding contacts connecting said ringing circuit and said storage circuit in parallel with said line circuit when said switch is in its non-busy position, and contacts connecting said supervision loop and receiver circuit to said line circuit while breaking said ringing and storage circuits when said switch is in its busy position.

10. A telephone system, as claimed in claim 9, in which said blocking device is an electrolytic condenser.
